UNITED STATES PATENT OFFICE.

MYRON H. PATRICK, OF SCHENECTADY, NEW YORK.

FUSE PLUG.

Application filed November 17, 1924. Serial No. 750,315.

This invention relates to an improved fuse plug, and it has more particularly reference to a device of this class which embodies a readily renewable fuse.

5 It is my object to generally improve upon plugs of this class by providing one of extreme simplicity and durability, wherein a hollow cup-shaped plug is employed with a quickly renewable fuse located therein, 10 there being a removable closing cap for the open end of the plug, permitting access to be had to the interior for replacing the fuse.

Other features and advantages of the invention will become apparent from the following description and drawings.

In the accompanying drawing, forming a part of this application, and in which like numerals are employed to designate like parts throughout the same:

20 Figure 1 is a central vertical section, through a fuse plug constructed in accordance with the present invention.

Figure 2 is a top plan view thereof.

Figure 3 is a bottom plan view.

25 Figure 4 is a detail view of the renewable fuse, and

Figure 5 is a detail view of the fuse mounting element.

Referring to the drawing in detail, it will be seen that the fuse is composed mainly of a cup shaped body 1, which, in practice is preferably composed of hard rubber or its equivalent. At its top, the body is surrounded by a flange 2, which is threaded 35 around its periphery for purposes to be hereafter more fully described. The bottom of the body is formed with a central projection having a screw threaded socket for reception of a contact screw 3. Adjacent this

40 projection is a recess 4, in which a small screw 5 is located. The screw 5 serves to clamp the inturned end of a metal shell 6 in place. The shell is threaded, in the usual way, for reception in the standard socket.

45 The body is also provided, at diametrically opposite points with vertical bores having inturned lower ends, and a pair of substantially U-shaped brass strips 7, and 8, are located in these. The inner or lower in-

50 turned ends of the strips are connected with the screws 3 and 5 respectively. The upper inturned ends terminate in spaced relation, and constitute forks for a renewable fuse designated generally 9. In the present instance, this renewable fuse comprises an elongated piece of insulation 10 (see Fig-

ure 5) and a fuse link 11, (see Figure 4). The link is provided at its opposite ends with eyes 12, which register with openings 13, in the opposite ends of the fiber piece 10. 60 This piece or element is preferably provided between its ends with an outstanding tab 14 which constitutes a finger piece and is adapted to carry a mark indicating the amperage of the fuse link. The link may be 65 secured to the fiber in any appropriate manner, to provide a unit which may be more readily handled. Owing to the small size of the link, it will be otherwise inconvenient to handle. 70

The fuse unit so made up is placed upon the inturned end of the brass strips 7 and 8, and screws 15 are passed through the registered openings to hold it in place.

75 A brass cap 16 is threaded upon the aforesaid flange 2 and has a central opening. Held within the cap by a washer 17 is a mica disc 18, serving to protect and render the fuse visible.

In practice, the improved plug is used 80 in the same manner as the ordinary plug, but it is advantageous thereover, because the fuse unit can be readily replaced if blown. Thus, instead of necessitating the provision of an entirely new plug, the removable cap 85 is simply taken off and a new fuse is inserted. It may be said here that the small screw 5 serves to hold the shell against rotation relative to the body and the threads of the shell and body are opposite to the 90 threads of the contact screw 3. This prevents unloosening of the last named screw, when removing or inserting the plug.

It is thought that the foregoing description will suffice, when taken in connection 95 with the accompanying drawing, to enable persons skilled in the art to which the invention relates to obtain a clear understanding of the same. For this reason, a more lengthy description is thought unnecessary. 100

Minor changes coming within the scope of the adjoined claims may be resorted to, if desired.

I claim:

A fuse plug comprising a cup-shaped 105 body, a pair of electricity conducting strips embedded in the walls of the body at substantially diametrically opposite points, the upper ends of said strips extending at right angles to the body portions and inwardly 110 towards each other and terminating in a plane with each other, said inturned ends

being provided with openings, means co-
operable with the opposite ends of said
strips for conducting electricity there-
through, an elongated fiber element pro-
vided at its opposite ends with openings
5 registrable with the openings in the in-
turned ends of said strips, said element be-
ing provided between its ends with a later-
ally directed finger-gripping tab, and a fusi-
ble link resting upon said fiber element and
10 provided at its opposite ends with eyes regis-

tering with the openings in said element,
and connecting bolts passing through said
eyes and through the openings in said ele-
ment and inturned strip-ends, the latter to-
gether with said fiber element and fusible
link and fastenings being located in the re-
cess of said cups to render them accessible
for replacement. 15

In testimony whereof I affix my signature.

MYRON H. PATRICK.
